WEIGHTED SNAG HOOK

Lawrence Lombardi, 6754 Hooker, and Walter Radovich,
1449 S. Yates, both of Denver, Colo.

Filed Jan. 4, 1962, Ser. No. 68,191

Term of patent 3½ years

(Cl. D31—4)

FIG. 1.

FIG. 2.

FIG. 3.

FIGURE 1 is a front elevation of a weighted snag hook showing our new design;

FIGURE 2 is a top plan view thereof; and,

FIGURE 3 is a bottom plan view.

The side not shown is substantially like the side shown.

We claim:

The ornamental design for a weighted snag hook, as shown and described.
